UNITED STATES PATENT OFFICE

140,502

DESIGN FOR A CHAIR

Walter J. Forster, St. Louis, Mo., assignor to Curtiss-Wright Corporation, a corporation of Delaware

Application July 20, 1944, Serial No. 114,474

Term of patent 7 years

(Cl. D15—8)

To all whom it may concern:

Be it known that I, Walter J. Forster, a citizen of the United States, residing at St. Louis, State of Missouri, have invented a new, original, and ornamental Design for Chairs, of which the following is a specification, reference being had to the accompanying drawings forming a part thereof.

In the drawings,

I claim:

The ornamental design for a chair, substantially as shown.

WALTER J. FORSTER.
